UNITED STATES PATENT OFFICE.

LEO C. HARDEBECK, OF ELK PARK, MONTANA.

SHOE-FASTENER.

1,191,781.

Specification of Letters Patent. Patented July 18, 1916.

Application filed May 11, 1914. Serial No. 837,813.

To all whom it may concern:

Be it known that I, LEO C. HARDEBECK, a citizen of the United States, residing at Elk Park, in the county of Jefferson and State of 5 Montana, have invented certain new and useful Improvements in Shoe-Fasteners, of which the following is a specification.

This invention relates to shoe fasteners, and one of the principal objects of the invention is to provide a shoe fastener of simple construction which may be formed entirely of leather or other flexible material and thus eliminating the use of metal as any part of the fastening device.

15 Another object of the invention is to provide a shoe fastener which shall be simple and quick to fasten and quick to unfasten and which will present a good appearance without the use of metal eyelets, hooks or 20 other fasteners.

Still another object of the invention is to provide a simple shoe fastening which can be used in lieu of buttons at the outer sides of the upper portion of the shoe, or which 25 can be used at the instep in lieu of laces.

These and other objects may be attained by means of the construction illustrated in the accompanying drawings, in which,

Figure 1 is a side elevation of the left shoe 30 showing a fastener made in accordance with this invention and the vamp portion of the shoe broken away. Fig. 2 is a sectional view taken on the line 2-2 of Fig. 1, and Fig. 3 is a horizontal section taken on the 35 line 3-3 of Fig. 1.

Referring to the drawing, the numeral 1 designates a sole, 2 the heel, 3 the quarter, 4 the vamp and 5 the upper of a shoe which may be of the usual or any suitable construction. 40 As shown in the drawing, the shoe is provided with an ankle opening formed on a curved line similar to the ordinary button shoe, and connected to the back portion of the upper or quarter of the shoe is a 45 series of guides, each formed of a piece of leather or similar material which will hold its shape. These guides are designated by the numeral 6 in the drawing and they comprise the upper portion connected by the 50 downwardly extending side portions 7 and outwardly extending feet 8 which are connected in any suitable manner to the back

portion of the upper or quarter. Any suitable number of these guides may be utilized, and while four are shown in the drawing, a 55 greater number or in some cases, a smaller number of these guides may be sufficient. The front portion 5 of the upper is provided with a series of openings 9 which coincide in position with the guides 6. 60

A strap 10 of a width to nicely pass through the guides 6 is connected at its lower end underneath the meeting edge of the vamp and upper, said strap being slightly enlarged at this point. The opposite end of the strap is preferably provided with a tapering point 11 to assist in threading the strap through the guides 6.

In securing the shoe to the foot, the upper portion 5 is drawn over toward the back 70 and the guides 6 are inserted through the openings 9 in the flap 5 and the leather tongue 10 is then first threaded through the lower guide and so on until it passes through the upper one. In unfastening the shoe, the 75 finger may be inserted between the guides for pulling out the strap. This operation is quick and can be done in the dark since the guides 6 may be threaded readily by the pointed end of the tongue without requiring 80 the use of the eyes.

From the foregoing it will be obvious that a shoe fastening made in accordance with this invention may be used at the instep in lieu of lacing, at the side in lieu of buttons 85 or can even be used at the back line of the quarter if desired.

Various changes in the details of construction may be resorted to without departing from the spirit and scope of the invention 90 as defined in the claim.

What is claimed is:—

The combination with the upper quarter and vamp, the upper and quarter being formed with a curved ankle opening and 95 said upper being provided with a plurality of elongated openings arranged in a curved line, of a plurality of guides consisting of upper portions, downwardly extending side portions formed on the ends of the upper 100 portions and provided with their lower ends bent at right angles to form feet adapted to rest on the quarter, means for securing the feet to the quarters and being so arranged

that the side portions and upper portions
may extend through the openings of the
upper, and a strap approximately the width
of the upper portions of the guides secured
5 at one end between the meeting edges of the
vamp and quarter and adapted to be
threaded through the guides and upper.

In testimony whereof I affix my signature
in presence of two witnesses.

LEO C. HARDEBECK.
